US00D504778S

(12) **United States Design Patent** (10) Patent No.: **US D504,778 S**
(45) Date of Patent: **** May 10, 2005**

(54) **FABRIC**

(75) Inventor: **François-Xavier Mariani**, Legnano (IT)

(73) Assignee: **Polar Bear Trading Ltd. (MT)**

(**) Term: **14 Years**

(21) Appl. No.: **29/195,736**

(22) Filed: **Dec. 16, 2003**

(30) **Foreign Application Priority Data**

Jul. 21, 2003 (EM) 54531

(51) LOC (7) Cl. **05-05**

(52) U.S. Cl. **D5/20**

(58) Field of Search ..... D5/1, 2, 3, 7-8, D5/11, 19-20, 23, 25, 30, 32, 41, 43, 45-47, 49, 50, 52-64, 66, 99; D2/749, 994; D6/582, 583, 595, 596, 598, 603-605, 608, 613, 616, 617, 622; 428/17, 18, 151, 154, 156, 171, 187, 198, 199, 904.4, 542.2, 919, 542.6; D24/124, 125; D25/142, 152; 5/413 AM, 709; D7/396.4, 396.5; 162/134, 140, 231; 156/148, 209
